US0D1087253S

(12) **United States Design Patent** (10) **Patent No.:** **US D1,087,253 S**
(45) **Date of Patent:** **** Aug. 5, 2025**

(54) **EXERCISE MACHINE COMPONENT**

(71) Applicant: **TONAL SYSTEMS, INC.**, San Francisco, CA (US)

(72) Inventors: **Robin Barata**, San Francisco, CA (US); **Nina Samarguliani**, Oakland, CA (US); **Daniel K. Harden**, Carmel, CA (US); **Yale F. Shaw**, San Francisco, CA (US); **Ariel D. Turgel**, San Francisco, CA (US)

(73) Assignee: **TONAL SYSTEMS, INC.**, San Francisco, CA (US)

(**) Term: **15 Years**

(21) Appl. No.: **29/928,731**

(22) Filed: **Feb. 14, 2024**

CLAIM

The ornamental design for an exercise machine component as shown and described.

DESCRIPTION

FIG. 1 is a front-right side perspective view of an exercise machine component according to an embodiment of our new design;

FIG. 2 is a front-left side perspective view of the exercise machine component of FIG. 1;

FIG. 3 is a front elevation view of the exercise machine component of FIG. 1;

FIG. 4 is a right side elevation view of the exercise machine component of FIG. 1;

FIG. 5 is a left side elevation view of the exercise machine component of FIG. 1;

FIG. 6 is a top plan view of the exercise machine component of FIG. 1; and,

FIG. 7 is a bottom plan view of the exercise machine component of FIG. 1.

The broken lines shown in the drawings are for purposes of illustrating portions of the exercise machine component that form no part of the claimed design.

1 Claim, 7 Drawing Sheets
